CLAIM

We claim the ornamental design for a cup lid, as shown and described.

DESCRIPTION

FIG. 1 is a perspective view of a cup lid, as viewed from above and one side, with a sealing element in a closed position.

FIG. 2 is a rear elevation view of the cup lid of FIG. 1.

FIG. 3 is a front elevation view of the cup lid of FIG. 1.

FIG. 4 is a side elevation view of the cup lid of FIG. 1.

FIG. 5 is an opposite side elevation view of the heel of the cup lid of FIG. 1.

FIG. 6 is a top plan view of the cup lid of FIG. 1.

FIG. 7 is a bottom plan view of the cup lid of FIG. 1; and,

(Continued)

FIG. 8 is a perspective view of the cup lid of FIG. 1, as viewed from above and one side, with the sealing element in an open position.

The broken lines depict portions of the cup lid and form no part of the claimed design.

1 Claim, 6 Drawing Sheets
